UNITED STATES PATENT OFFICE.

JOHN WEIL, OF MANSFIELD, OHIO.

SWING.

1,214,854.

Specification of Letters Patent. Patented Feb. 6, 1917.

Application filed February 21, 1916. Serial No. 79,521.

To all whom it may concern:

Be it known that I, JOHN WEIL, a citizen of the United States of America, residing at Mansfield, in the county of Richland and State of Ohio, have invented certain new and useful Improvements in Swings, of which the following is a specification.

This invention relates to a swinging parallel bar mechanism for swings in combination with a stand, canopy top, and swing frame.

One of the objects of this invention is to provide a swinging mechanism comprising pivotally and removably mounted, spaced apart, parallel supporting bars, which are hung from the upper portion of the ends of a stand constructed to provide spaced apart, open ends, the free ends of the parallel bars being pivotally secured to the base bars of the frame of the swing, thereby movably supporting and suspending the swing frame for horizontal movement.

A further object is to provide a swing that will permit the supporting member thereof to be constantly maintained upon a horizontal plane during its swinging movement and while at rest thereby obviating the tilting of the supporting member when it is manipulated to force it to oscillate for the purpose intended.

Another object consists in providing a swinging mechanism that can be disassembled or assembled for operation in combination with a swing stand and swing frame without the use of tools or the removal of bolts or other fastening means, and further providing means of constructing the swing stand, swinging mechanism and swing frame so that they can be used conjointly; said elements also being arranged and adapted to be folded in a compact form to economize in space for shipping purposes and for ease and convenience in transporting same.

Another object is to provide a swing frame with legs having base connecting bars provided thereon to which the parallel bars of a swinging mechanism are pivotally attached instead of being attached directly to the supporting member of the swing frame (as is practised in the construction of the ordinary swing mechanism) thereby permitting the use of longer parallel supporting bars without increasing the height of the swing or its allied parts, the resultant being that the radius of the arc traveled by the supporting bars is greatly increased.

A further object of this invention is to suspend the swing frame for oscillation by pivotally attaching the free ends of spaced parallel supporting bars to the base bars of the swing frame, thereby providing for increased travel of swing frame and parallel supporting bars without increasing the grade of travel of said mechanism as would follow if it were desired to increase the travel of an ordinary swing frame which is ordinarily supported from one pivot for oscillation.

A further object of this invention is to provide a double acting power crank mechanism which is operated by a treadle or the like for imparting movement to the swinging mechanism.

Another feature of this invention is in obtaining a greater distance of travel of the swinging mechanism which is accomplished by constructing the sides of the seat with legs, and providing base bars therefor which lie near the floor level, permitting the use of long bars by means of which the radius of the arc traveled by the swing mechanism is greatly increased, due to the increased distance from the fixed points of suspension on the swing stand, to the movable points of suspension on the base bars of the swing frame.

I attain these and other objects by the mechanism illustrated in the accompanying drawing in which:

Fig. 1 is a perspective view of the swing stand, swinging mechanism, swing frame, and operating mechanism therefor, showing the parts assembled and ready for use.

Fig. 2 is a front elevation of the swing frame showing it in position for use.

Fig. 3 is a front view of the swing frame showing the parts folded or collapsed for shipping or transporting purposes.

Fig. 4 is a side elevation of the swinging and operating mechanism, and it also shows an end view of the swing frame pivotally supported by the swinging mechanism. This view shows the swinging mechanism pivotally attached to the ceiling of a porch instead of a stand.

Fig. 5 is a perspective view of the stand showing the parallel bars hung from the stand and suspending the base bars of the sides of the swing frame, also showing an adjustable and folding canopy top frame mounted upon the stand.

Fig. 6 is an end elevation in section at A A Fig. 5 of the combined mechanism showing one end of the swing frame, operating mechanism, the stand and canopy top frame being shown in position for normal use in full lines and in its adjustable position in dotted lines, as used for outdoor sleeping.

Fig. 7 shows detail side and end views of the means of pivotally and removably mounting the parallel bars to the swing frame and stand.

In the drawings reference numerals 1 and 2 indicate frames which constitute the ends of a stand. The frames are hinged to the floor bars 3 and 4 and rigidly locked in a vertical position when used for supporting the swinging mechanism and swing frame.

A part of the swinging parallel bar mechanism comprises two bars 5 and 6 of predetermined length which are pivotally hung from the upper portions of the frames 1 and 2 and arranged thereon to align with each other. Bell cranks 7 and 8 are pivotally hung from the upper portion of the frames 1 and 2.

Bars 9 and 10 of shorter length than the bars 5 and 6 are pivotally attached to the bell cranks and suspended therefrom. The link bars and connected bell cranks provide one part of the swinging mechanism and the bars 5 and 6 the other part. The respective links, bell cranks and bars are pivotally suspended from the upper portion of the frames, spaced apart a predetermined distance from each other and held on a plane, in alignment with, and in parallel relation to each other thereby forming a swinging parallel bar mechanism to suspend the moving frame.

A swing frame is constructed of sides 11 and 12 having legs 13 and 14 preferably formed integral with base connecting and supporting bars 15 and 16. The free ends of the short bars 9 and 10 and bars 5 and 6 are pivotally attached to the base bars. L shaped brackets 17 are secured to the sides 11 and 12 of the swing frame leaving the top portion thereof spaced apart from the sides.

A supporting frame member 18 preferably made of angle iron is supported upon the brackets, one part of the angle iron fitting in the space between the sides of the swing frame and the top portion of the L shaped brackets. The gravity of the supporting member and the juxtaposition relation of its ends to the sides of the swing frame rigidly maintain the sides of the swing frame in a vertical position.

Braces 19 are pivotally and angularly arranged and connected to the sides of the swing frame on one end and their opposite ends are pivotally connected to the supporting member, thereby movably connecting the sides and supporting member to permit

the folding of the elements comprising the swing frame for convenience in shipping and transporting.

The supporting member can be arranged and designed for a bed, cot, couch, seat, chair or the like as desired. A back 20 is hinged to the supporting member and is held in a predetermined inclined position by a bar 21. The bar is preferably provided with hooked ends to engage the apertures 22 in the sides of the swing frame and the back 20 (see Figs. 1 and 2).

A folding and adjustable canopy top frame 23 is mounted upon vertical standards 24. The canopy top frame is held and can be adjusted and maintained at any height desired with respect to the stand by the manipulation of the strap clamps 25 (see Figs. 5 and 6).

The preferable manner of hanging the parallel bars for rapid and convenient assembling and disassembling of the swing frame without tools, the removal or use of bolts, or the like, consists in securing rivets 26 or the like to the stand having enlarged concentric heads 27, the enlarged heads passing through apertures 28 thereby permitting the body of the rivet to engage the slots 29 and pivotally support the parallel bars upon the end walls of the slots.

The operating mechanism of the swinging mechanism is constructed and connected thereto as follows: A treadle 30 is pivotally connected to the base bars 15 and 16 extending outwardly in front of the supporting member, and link levers 31 and 32 are connected to the treadle on one end and the opposite ends are connected to the free apexes of the bell cranks supporting the treadle in close proximity to the supporting frame member.

When it is desired to disassemble the complete swing mechanism for shipping or transporting purposes, the parallel bars and operating mechanism including the treadle are removed and the sides of the swing frame are folded from the position shown in Fig. 2 underneath the supporting member and the back is folded upon the top of the supporting frame member (see Fig. 3).

The end frames of the stand are folded toward each other and lie adjacent to the floor bars. The complete swing mechanism being then folded in compact form, it can be easily and conveniently shipped or transported.

Attention is called to the fact that in Fig. 4 the swinging mechanism is shown attached to a ceiling or the like in which case it is obvious that the stand is not used. In Fig. 6 the dotted line position of the canopy top frame is shown as being the preferable adjusted position when the swing is used out of doors, for sleeping purposes.

The operation of the swinging mechanism

which carries the swing frame is as follows: Pressure is exerted upon the treadle in a downward direction and this has the effect of exerting a pull through the medium of the link levers upon the bell cranks and simultaneously therewith the treadle pushes the base bars which are attached to the legs of the sides of the swing frame and the parallel bars rearward, thereby applying the power of a double crank mechanism to impart movement to the swing mechanism when pressure is exerted upon the treadle as described.

Attention is called to the fact that by a slight pressure upon the treadle, movement is imparted to the swing because of the fact that the swing is suspended upon a parallel bar swing mechanism which greatly elongates the swinging arc traveled by the parallel bars; hence the grade ascended by the swinging mechanism carrying the load is greatly reduced and the driving power necessary to drive same also decreased.

What is claimed is:

1. In a swing, a stand, a parallel bar swinging mechanism, pivotally supported by the stand and movable for imparting movement to the swinging mechanism by moving certain of the pivotal connections between the swinging mechanism and stand.

2. In a swing, a stand, a parallel bar swinging mechanism, pivotally connected to the stand, certain of the pivotal connections having a plurality of pivotal points and means for imparting movement to the swinging mechanism through operation of the plural pivotal points.

3. In a swing, a stand, a parallel bar swinging mechanism, certain of said bars including bell crank connectors and means for imparting movement to the swinging mechanism through operation of the bell crank connectors.

4. In a swing, a stand, a swinging frame, bars connecting the swinging frame and stand, certain of the bars including bell crank connectors intermediate the same and

stand, and means for imparting movement to the frame by operation of the bell crank connectors.

5. In a swing, a stand, a swinging frame, bars pivotally connected to similar ends of the frame and to the stand, bars pivotally connected to the opposite end of the frame, bell cranks connected to said latter bars and to the stand, an operating member supported on the frame and connections between said member and bell cranks for imparting movement to the frame.

6. In a swing, a stand, a frame including side and base bars projected in both directions beyond the sides, swinging bars pivotally connected to the rear ends of the base bars, and to the stand, swinging bars pivotally connected to the forward ends of the base bars, bell cranks pivotally connected to said last mentioned swinging bars and to the stand, an operating member pivotally connected to the base bars and connections intermediate said operating member and bell cranks.

7. In a swing, a folding stand, a parallel bar swinging mechanism supported by the stand, a folding swing frame carried by the parallel bar swinging mechanism, a double crank operating mechanism connected to the parallel bar swinging mechanism and forming part thereof to impart movement thereto.

8. In a swing, a stand, a swing frame, and swinging mechanism supported by the stand and supporting the frame, said swinging mechanism including a plurality of members located at relatively right angles with respect to the stand when the parts are at rest, whereby the swinging mechanism is of the parallel bar type inducing a normally horizontal movement of the swing frame, in the operation of the structure and means connected to the swinging parallel bar mechanism to impart movement to the frame.

In testimony whereof I affix my signature.

JOHN WEIL.

Witness:

JOHN H. COSS.
